UNITED STATES PATENT OFFICE.

JOHN F. GRACE, OF ARLINGTON, NEW JERSEY, ASSIGNOR TO WORTHINGTON PUMP AND MACHINERY CORPORATION, OF NEW YORK, N. Y., A CORPORATION OF VIRGINIA.

CONDENSER.

Application filed March 8, 1928. Serial No. 260,018.

This invention relates to steam condensers of the surface type and an object of the invention is to provide a condenser in which leakage of cooling water, circulated through 5 the tubes of the condenser, into the steam chamber and its mixing with the condensate will be prevented.

A further object of the present invention is to provide a condenser structure in which 10 both ends of the condenser tubes may be expanded into the tube heads to provide fluid tight connections and to provide means for compensating for expansion and contraction of the tubes due to temperature variances and also to accommodate or compensate for unequal expansion of the respective 15 tubes due to difference in temperatures locally within the condenser.

The present invention embodies a condenser having a floating water box to which 20 one of the tube sheets or heads of the condenser is attached and an expansion joint between the tube sheet and condenser shell to permit movement of the tube sheet and 25 water box relative to the shell to compensate for expansion and contraction of the condenser tubes under heat variances, and it also embodies flexible supporting or suspension means establishing movable connection 30 between the water box and condenser shell to permit supported movement of the water box to compensate for localized variances of temperatures within the condenser.

With these objects in view, the invention 35 consists in various features of construction and combination of parts, which will be first described in connection with the accompanying drawings, showing a condenser of the preferred form embodying the invention, and the features forming the invention 40 will be specifically pointed out in the claims.

Fig. 1 is a side elevation partly in section 45 of a condenser constructed in accordance with this invention.

Fig. 2 is an end elevation of a condenser constructed in accordance with this invention.

Fig. 3 is a detailed side elevation showing 50 a slight modification in the flexible suspension means, and

Fig. 4 is a detailed cross section on the line 4—4 of Fig. 3.

Referring more particularly to the draw-

ings, the improved condenser comprises a 55 shell 1 having an exhaust steam inlet 2 through which the exhaust steam to be condensed enters the condenser shell 1 and passes transversely therethrough about the cooling tubes 3. Cooling water for condensing the steam is circulated through the tubes 3 and the water boxes 4 and 5 while the condensate passes to the hot well 6 from which it is drawn in any suitable manner. To prevent leakage of the circulated cooling water 60 into the condenser chamber and its resulting mixing with the condensate, the tubes 3 have their ends expanded into the tube heads or sheets, one of which is shown at 7 in the drawings. While the tubes 3 are shown as 70 expanded into the tube heads, it is to be understood that they may be connected to the tube heads or sheets in any suitable manner so as to provide a fluid tight joint.

Owing to the fluctuation of temperatures 75 within a condenser operated under varying loads, it is necessary to provide compensation for the expansion and contraction of the tubes 3 under the heat variances due to the varying load, so as to prevent rupturing 80 of the connections between the tubes and the tube sheets.

In the present embodiment, tube sheet 7 is attached to the water box 5 and they are both connected to the condenser shell 1 by 85 an expansion joint 8 which is a gasket of flexible material, preferably rubber or a combination of rubber and cloth or any suitable material found adaptable for the purpose, which will not corrode or deteriorate upon 90 contact with the water and steam in the condenser shell and which will embody sufficient elasticity to permit of the necessary relative movement between the tube sheet and the shell 1 to compensate for expansion and contraction 95 of the tubes. The gasket 8, which forms the expansion joint engages between the tube sheet 7 and the water box 5, and is attached to the casing 1 by clamping ring 9 as clearly shown in Fig. 1 of the drawings. 100

To provide supported movement of the water box 5 which moves with the expansion and contraction of the tubes, brackets 10 are attached to the shell 1 above the plane intersecting the horizontal axis of the water box while brackets 11 are attached to the water box below the horizontal plane bisecting the axis of the water box and flexible 105

or spring suspension strips 12 are attached to the brackets. The strips 12 are preferably of spring steel embodying sufficient strength to support the weight of the water box and sufficient flexibility to permit its movement under the force created by the expansion or contraction of the tubes.

In Figs. 3 and 4 of the drawings a slight modification of the invention is shown and in this modified form the flexible suspension members 12' are made up of laminated spring strips in lieu of single spring strips as shown in Figs. 1 and 2. In all other respects the modified form shown in Fig. 15 is similar to the preferred form illustrated in Figs. 3 and 4.

It will be understood that the invention is not to be limited to the specific construction or arrangement of parts shown but that these may be modified widely within the invention defined by the claims.

What is claimed is:

1. In a surface condenser, a shell, a water box, and suspension springs connecting the water box and shell to permit limited movement of the water box relative to the shell.
2. In a surface condenser, a shell, a water box, and laminated suspension springs connecting the water box and shell to permit limited movement of the water box relative to the shell.
3. In a surface condenser, a shell, a water box, a tube sheet connected to the water box, a flexible gasket connecting the water box and shell, and springs forming a movable supporting connection between the shell and water box.
4. In a surface condenser, a shell, a water box, a tube sheet connected to the water box, a flexible gasket connecting the water box and shell, and springs forming a movable supporting connection between the shell and water box, the active part of said flexible gasket being exposed exteriorly of the condenser shell and water box.
5. In a surface condenser, a shell, a water box, a tube sheet connected to said water box, and suspension springs connected to said shell above the plane of the horizontal axis of the condenser and to the water box below the plane of the horizontal axis of the condenser.
6. In a surface condenser, a shell, a water box, a tube sheet connected to said water box, and suspension springs connected to

said shell above the plane of the horizontal axis of the condenser and to the water box below the plane of the horizontal axis of the condenser, and a flexible gasket forming an expansion joint between said water box and shell.

7. In a surface condenser, a shell, a water box, a tube sheet connected to said water box, and suspension springs connected to said shell above the plane of the horizontal axis of the condenser and to the water box below the plane of the horizontal axis of the condenser, and a flexible gasket forming an expansion joint between said water box and shell, the active part of said flexible gasket being exposed exteriorly of the condenser shell and water box.

8. In a surface condenser, a shell, a water box, a tube sheet carried thereby, tubes having fluid tight connection with said tube sheet, a fluid tight expansion joint between said water box and shell, and laminated springs forming a supporting connection between the shell and water box.

9. In a surface condenser, a shell, a water box, a tube sheet carried thereby, tubes having fluid tight connection with said tube sheet, a fluid tight expansion joint between said water box and shell, and laminated springs forming a supporting connection between the shell and water box, the active part of said expansion joint being exposed exteriorly of the shell and water box.

10. In a surface condenser, a shell, a water box, a tube sheet carried thereby, tubes having fluid tight connection with said tube sheet, a fluid tight expansion joint between said water box and shell, brackets on said shell, brackets on the water box, and flexible springs connected to said brackets to provide yieldably supporting connection between the shell and water box.

11. In a surface condenser, a shell, a water box, a tube sheet carried thereby, tubes having fluid tight connection with said tube sheet, a fluid tight expansion joint between said water box and shell, brackets carried by said shell above the plane of the horizontal axis of the condenser, brackets carried by the water box below horizontal plane of the condenser, and spring strips connected to said brackets for providing yieldable supports for the water box.

In testimony whereof I affix my signature.
JOHN F. GRACE.
